DESIGN FOR A PENCIL

Guy J. Blakeman, Knob Lick, Ky.

Application November 2, 1946, Serial No. 134,476

Term of patent 14 years

(Cl. D74—24)

To all whom it may concern:

Be it known that I, Guy J. Blakeman, a citizen of the United States and a resident of Knob Lick, in the county of Metcalfe and State of Kentucky, have invented a new, original, and ornamental Design for Pencil, of which the following is a specification, reference being had to the accompanying drawing, forming part thereof.

Fig. 1 is a front elevational view of a pencil, showing my new design,

Fig. 2 is a side elevational view; and

Fig. 3 is a top plan view.

I claim:

The ornamental design for a pencil, substantially as shown.

GUY J. BLAKEMAN.
